SKI POLE CONSTRUCTION

Raymond C. Taft, Wallingford, Vt., assignor to
The American Fork & Hoe Company, Cleveland,
Ohio, a corporation of Ohio

Application January 12, 1943, Serial No. 472,146

1 Claim. (Cl. 280—11.37)

My invention relates to ski poles and relates more particularly to the ring shaped snow shoe usually mounted thereon.

It is an object of my invention to provide a ski ring of the type referred to which can be readily and easily assembled.

Another object of my invention is to provide a ski ring of the type referred to which will be light in weight and yet sturdy and strong.

Another object of my invention is to provide a ski ring of the type referred to which may be economical in manufacture and efficient in use.

Other objects of my invention and the invention itself will be more apparent from the following description and drawing, in which drawing:

Fig. 1 is a perspective view, partly broken away, showing an illustrative embodiment of my invention;

Fig. 2 is a plan view of the ring forming member of my invention;

Fig. 3 is a plan view of one of the radial thongs;

Fig. 4 is a plan view of one of the clip members;

Fig. 5 is a fragmentary view showing the ring and thong assembly.

The ski pole shown in the attached drawing comprises a shaft 1 and is provided with a loop formed from a leather strap 2 secured to the upper end of said shaft, said loop being adapted for use as a handle. The customary spike 3 is secured to the shaft at its lower end and spaced therefrom on the lower end portion of the shaft a preferably flat ski ring or snow shoe 4 is secured to the shaft, said ring surrounding the said shaft portion.

The ring or shoe 4 is preferably formed from two or more convolutions of a spirally wound strip of wood, the convolutions being glued or otherwise secured together. The resulting ring serves as a point of attachment for a plurality of thongs 6, preferably three in number, which are formed of buckskin, rawhide or the like. The thongs 6 are preferably formed from rectangular flat strips of leather and are provided with a narrow slit 7 of considerable length. Said thongs are placed on top of each other and secured by means of clips 8 at their opposite ends to the ring member 4, said straps being so disposed as to be secured at approximately equally spaced intervals about the ring and to overlap each other at their center portions thus forming sufficient surface area to provide the necessary grip on the surface of the snow.

The clip members 8 are generally rectangular in form with slightly rounded end portions and are provided with apertures 9—9 at opposite ends

thereof, said apertures corresponding to apertures 10—10 in the thong members 6—6.

In securing the thong members 6 to the ring 4, the clip is folded over the ring and a rivet 11 is projected through the then aligned apertures 9—10—9. The two reaches of the clip member 8 are then bent inwardly or crimped, as at 8'—8', intermediate the ring engaging portion 12 and the thong engaging portions 13. This crimping is preferably performed chiefly on the marginal edges of the clip, thus producing a permanent distortion, serving to further encircle and clamp the convolutions of the ring, and to shorten the clip reaches and thus tension the thong.

It is to be noted that said secure fastening is accomplished without weakening the ring member in any way as by the projection of pins, etc., therethrough. Further, it has been found that such a construction furnishes a light weight ring 15 having yieldable cross thongs and a rigid fastening.

The ski pole 1, as illustrated, is projected through the slits 7 of the cross thongs and fastened to the thong members 6 by means of laces 25 or additional strap members 14, as shown, to securely anchor the thongs against displacement.

The clip members 8 further act as reinforcing members for the light weight ring and inasmuch as these are preferably formed of a light weight metal do not unduly increase the weight thereof. The crimped portions 8'—8' of the clip members moreover restrict the thongs from lateral movement as a portion thereof is wedged within the 30 crimped portion of the clips 8. The remaining portions of the thong members 6 are yieldable, however, in the sense that the same may be easily secured to the shaft by the straps 14 and also have a certain resiliency upon contact with ice 35 or snow, as may be desired.

While I have described my invention in connection with a preferred embodiment thereof, it is to be understood that numerous and extensive departures may be made therefrom without 40 departing from the spirit of my invention and the scope of the appended claim.

I claim:

A ski ring comprising in combination a light weight substantially flat ring member consisting 45 of a plurality of convolutions of a relatively thin strip of wood or light flexible or like indenturable material of substantially equal width with the contacting faces of adjacent convolutions adhesively secured together, the ring so formed being 50 of rectangular flattened cross sectional shape, a

plurality of substantially flat cross members of substantially flexible material, said cross members being of a lesser length than the inner diameter of the ring member, a plurality of substantially flat clip members, each said clip member composed of an initially flat strip of bendable sheet metal medially so bent as to form a loop, the inner surface of the yoke thereof being adapted to fit the peripheral surface of the ring and the side arms thereof adjacent said yoke adapted to tightly embrace the upper and lower planar surfaces of the ring, and the ends of said arms being perforated for the reception of rivets or the like projected through an end of one of said cross members with said cross member end interposed between the clip ends, both arms of each said clip member in place to interconnect a cross member with said ring being distorted by a

10 crimping operation to sharply deflect the portion of each said arm disposed between said ring and the adjacent cross member end inwardly to substantially contactingly embrace the intra-peripheral surface of the ring portions of said inwardly bent arms and sufficiently distorted outwardly therefrom as to indenture said clip end portions and in turn the cross members held therebetween, the deformation and indenturing of said clip arms so shortening the length of said arms as to cause said thereby shortened clip arms operating through said rivet to draw said cross members taut, said cross members extending diametrically in centrally superposed relation across the ring and the indenturing of said clip arms preventing sliding displacement of said clip members on said ring.

RAYMOND C. TAFT.
